AUTOMATIC-CONTROL DEVICE

Application filed January 25, 1928. Serial No. 614,940.

My invention relates to an automatic control device involving a pair of alternating current motors with intermediate differential gearing for controlling the feeding movement of a machine in accordance with the resistance encountered by the cutter.

Other objects of my invention will become evident from the following detailed description taken in conjunction with the accompanying drawings, wherein Fig. 1 and Fig. 2 are curve charts illustrating certain characteristics of electric motors that are employed in connection with my invention;

Fig. 3 is a semi-diagrammatic view of an earth-drilling apparatus that is adapted to employ my improved method of automatic control;

Fig. 4 is a semi-diagrammatic view of a modified form of apparatus for utilizing the principles of my invention; and

Fig. 5 is a similar view of a further type of apparatus utilizing the principles of my invention for another purpose.

My invention is particularly adapted to oil-well drilling and the like, whereby the complicated cycle of hand-controlled operation during the rotary drilling of a well is accomplished automatically and at a maximum speed consistent with safety of operation. In such drilling operations the work of the driller includes several different cycles, one of which begins when the rotating bit just touches the bottom of the hole and ends with the swivel that supports the drill being located close to the rotary table. That is to say, such a cycle corresponds to the completion of 20 to 40 feet of well.

Depending upon the earth formations encountered this cycle may last some hours, unless interrupted by the changing of bits for any reason. The drill will encounter both soft and hard materials and the driller has been forced in the prior art to advance the bit intermittently in accordance with his best judgment. In other words, he frees the brake

band from the cable drum so that the drum may move through a short arc, thus lowering the drill stem and allowing some of its weight to be borne by the bit as the bottom of the well is touched. Then the driller tightens the 50 brake band to hold the drum stationary until he believes that the rotating bit has cut itself clear or nearly so. This cycle must be continually repeated as the depth of the well increases.

The pressure on the bit is a maximum at the instant of checking the drum movement, that is when the material is first encountered, but diminishes to zero when the drill cuts itself clear. The progress of the bit, measured in either time or distance, is thus only one half of what it would be if the pressure were maintained at a maximum safe value, throughout. In other words, automatic feed at such constantly regulated pressure will advance the tool twice as fast as the best hand regulation, and in actual practice this difference will probably be still greater.

The drill pipe may weigh as much as 50,000 pounds, although not more than a small fraction of this weight, for example, 4,000 pounds, should actually be carried by the bit itself, the remaining weight being supported by the suspending hook. If this pressure is exceeded, the cutting edge of the bit will be quickly dulled or chipped and, in many cases, still more serious effects have occurred, such as bending of the drill pipe, breaking of the bit or pipe, and overstressing the drilling plant.

However, by the use of the method herein set forth, all such troubles are prevented, since the drilling pressure is automatically regulated in accordance with the material being drilled through, that is to say, the resistance actually encountered by the cutting edge of the tool.

Referring first to Fig. 3 of the drawings, the apparatus here semi-diagrammatically shown for utilizing my novel method of drill-

ing comprises a suitable rotary drill 1, which is connected in a familiar manner with a draw works drum device 2 to be governed by means of a pair of electric motors 3 and 4, between which is interposed a suitable differential movement or mechanical couple 5, for purposes to be set forth. The drum device 2 is provided with the usual hand brake apparatus 6.

10 The drill 1 is provided with the usual square or fluted shank 7 for engaging a rotary table or bevel gear 8 and is suspended from a crown block pulley 9 by means of a rope or cable 10 that is wound upon the main drum portion 11 of the draw works drum device 2.

15 The two electric motors 3 and 4, the first of which is primarily adapted to effect rotary movement of the drill 1 and the other of which 20 is adapted to effect a regulating or controlling action, are adapted to be driven in opposite directions, as indicated by the arrows, by means of suitable electrical connections to a generator G or other source of energy. In 25asmuch as the particular electrical connections employed are not pertinent to my present invention, no further illustration or description thereof is considered necessary. I 30 preferably employ three-phase induction motors, although my invention is not so limited in its application.

The operating shaft of the driving motor 3 is shown as directly connected to a bevel gear-wheel 13 constituting one outer part of 35 the differential movement 5. The operating shaft of the regulating motor 4 is likewise shown as directly connected to a second bevel gear-wheel 15 constituting the other outer portion of the differential device. The two 40 gear-wheels 13 and 15 are adapted for jointly meshing with an intermediate or differential member or gear-wheel device 19, which is mounted within and secured to the drum 11. It will be understood that my invention is not 45 in any way restricted or limited to the use of the differential movement herein shown, but that any other device for accomplishing the same results may be utilized. One other form 50 of differential movement will be later described in connection with Figure 4.

For a more detailed description of the preferred form of differential movement, reference may be had to my co-pending application, Serial No. 454,451, filed March 22nd, 55 1921, for a power transmission system.

60 The directions of rotation of the two motors 3 and 4 are opposite, as previously mentioned and never reverse, motor 3 being adapted to drive the gear-wheel 13 in the direction corresponding to lowering the load on the draw works drum 2, whereas the other motor 4 drives the gear-wheel 15 in the direction corresponding to the raising of the load upon the drum. Consequently, when the two motors 65 3 and 4 both run at substantially synchro-

nous speed, the speed of the intermediate member, such as gear-wheel device 19 is substantially zero and, therefore, drum portion 11 is stationary. This corresponds to the "no load" condition of the drilling equipment.

70 When the heavy drill stem is hung over the suspending hook, torque is, of course, produced upon the drum member 11 and, as soon as the brake apparatus 6 is released by the driller, the drill 1 begins to move downwardly. The weight of the drill during such descent will cause the drum member 11 to drive the intermediate member 19 of the differential movement 5, which will, therefore, exert torque through the gearing upon the two electric motors 3 and 4. Consequently motor 3, 75 which is rotating in a direction corresponding to the descent of the drill, will be driven above synchronous speed and will act as a generator. On the other hand, motor 4, by reason of rotating in the opposite direction, will oppose 80 the action of the differential device 5 and will act as a motor.

85 It will be understood that the speeds of the motors 3 and 4 will depend upon their special characteristics and also upon the gear reduction that is embodied in the differential movement 5. For the sake of simplicity, it may be considered that the motors 3 and 4 are equal in size and alike in speed characteristics, and 90 handling only the illustrated load produced by the draw works drum 2 and the drill 1.

95 Neglecting the friction of the apparatus, the speed of the motor 3 will be exactly as much above synchronism as the speed of the motor 4 is below synchronism. As is well known, the speed of the intermediate gear-wheel device 19 of the differential device will 100 at all times be equal to one half of the difference in the speeds of the gear-wheels 13 and 15 and will be in the same direction as the faster moving outer gear-wheel. In other words, in the present case the intermediate gear-wheel device 19 will rotate in a direction 105 corresponding to the lowering direction of the drum member 11.

110 For example, if the slip of the regulating motor 4 under the load conditions assumed is 2%, its speed will thus be 98% of the synchronous speed, while that of the motor 3 will be 102% of synchronous speed, as indicated by the curve charts—Fig. 1 and Fig. 2—showing the relations between percentage of synchronous speed and percentage of full load of the motors 4 and 3, respectively, under 115 various operating conditions. The difference of motor speeds, divided by two, and taking into account the gear reductions, will give the speed of operation of the intermediate gear-wheel device 19 and of the cable drum 11. The actual movement of the drill bit may be 120 still further reduced in accordance with the number of lines in the suspending tackle, which is, of course, increased as the depth of the well increases.

- The regulating motor 4 thus absorbs energy from the supply circuit under the assumed condition, whereas the other motor 3 returns energy to the supply circuit by reason of being driven as a generator above synchronous speed. Apart from the relatively small losses, the two motors substantially balance each other, and the kinetic energy of the moving load with respect to the drum member 11 is alone utilized in lowering itself. Whenever the motor 3 is doing other work as a motor, such as driving the rotary table 8, the power produced by draw works drum 2 will thus assist the motor 3 in doing that work.
- The work of regulating motor 4 is always that of raising or tending to raise the drill out of the well. This statement holds true at all times, including periods when the drill is actually descending. The load on the motor 4 is equal to the torque produced by the drum member 11 multiplied by that speed at which the motor may be operating in accordance with its speed curve. Since the torque upon the drum member 11 is produced by the suspended weight of the drill 1, it follows that the load of motor 4 is at all times the exact measure of that weight. For a further discussion of this particular feature, reference may be had to my copending application, Serial No. 614,939 filed Jan. 25, 1923, Systems of control.
- The motive element perhaps best adapted for employment in my method of control is the familiar induction motor, since even relatively slight changes of torque thereof, are almost instantaneously reflected in speed changes, whereby movement of the drill 1 may be readily and instantaneously controlled.
- A drilling cycle corresponding to the length of the drill stem will now be described.
- When the drill is descending and the bit is not yet in contact with the bottom of the hole, the weight on the hook is maximum, and the load on motor 4 is maximum for that cycle. Therefore, the speed of motor 4 is then the lowest for that cycle.
- Motor 3, as previously shown, is driven above synchronous speed because of the descending drill stem. But it is also now driving the rotary table; this demands power even though the bit be not yet cutting, so that the actual load on motor 3 is always the resultant of the negative load produced by drum member 11 and the positive load produced by the rotary table 8. This resultant load is the least when the rotating drill is descending and has not yet started to cut. Therefore the speed of motor 3 is then the fastest for the cycle.
- The slower the speed of motor 4, the faster that of intermediate gear-wheel device 19, and the faster the speed of motor 3, the faster that of gear-wheel device 19. So that when the drill is descending and not cutting we have the condition of greatest difference in the speeds of motors 4 and 3, that is, the maximum rate of movement of drum member 11 and drill 1. Thus for a given weight of drill pipe and given motor characteristics, this rate of free movement will not be exceeded under drilling conditions and the advance for each revolution of the drilling tool may be limited as desired.
- Next assume that the drill bit touches bottom. Some of the weight of the drill pipe is then carried by the bit resting upon the bottom of the hole, and the weight on the hook is diminished by exactly this amount. The load on regulating motor 4 is diminished exactly in proportion to the pressure on the drill bit. Diminishing the load diminishes the slip of the motor so that motor 4 now runs faster.
- When the drill begins cutting, the load on motor 3 is increased in proportion to the diameter of the bit and the pressure on the bit. Increasing the load increases the slip, therefore, motor 3 runs slower. As the bit cuts itself clear, the reverse process takes place; the pressure on the bit lessens, the weight on the hook increases, the load on regulating motor 4 increases, the speed of motor 4 decreases. Likewise, the lessening bit pressure diminishes the resistance to the cutting tool, the load on motor 3 lessens and its speed increases. In this case, both motors 3 and 4 function to run differential member 19 and drum member 11 faster.
- Somewhere between maximum progress and zero progress a balance will be reached and the progress will be uniform through a given substance. The rate of progress depends upon the resistance offered to the tool by the material being cut, but this resistance is determined by the pressure on the bit, which in turn, is proportional to the weight on the hook, the load on motor 4 and its speed.
- If the bit is lowered into drilling contact with the hardest rock material, we have the extreme conditions of zero resistance to the drill as it approaches and maximum resistance to it on making contact. Obviously, for a given pressure the slowest progress will be through this hardest material. Progress through all other materials will be faster in inverse proportion to their resistance. In particular, the rate of longitudinal advance of the cutting tool, that is, the rate of penetration, through clay is so regulated that the cuttings are very thin shavings, which the circulating mud will readily dissolve, thus preventing "balled" bits. As previously shown, constant pressure on the bit will be maintained through a given substance, that is the maximum rate of progress will be made. If then the maximum safe pressure on the bit for the hardest rock be fixed as the limit of pressure, the rate of progress of the drill bit will be within the safe maximum for all other materials that can be drilled.

As previously stated,

It is well known that when the two bevel gears 13 and 15 rotate in opposite directions, the intermediate member 19 rotates at one-half of the difference in their speeds and in the direction of the greater speed.

With reference to driving motor 3 and regulating motor 4, therefore, the speed relations may be expressed by the equation,

10

$$(I) \quad \frac{1}{2}(Z_a - Z_c) = Z$$

where

15 Z_a = speed of motor 3

Z_c = speed of motor 4

Z = speed of intermediate member 19.

If the intermediate member 19 be connected to the drum 11 by a gearing or equivalent device, Equation (I) becomes

$$(II) \quad (Z_a - Z_c) K = Z_d, \text{ or}$$

$$(III) \quad Z_a - Z_c = S_d$$

25 where K is one-half the gear ratio change and is constant and

$$S_d = \frac{Z_d}{K}$$

30

When S_d is positive, it is evident that the movement of drum 11 is in the direction of motor 3, that is, in the lowering direction. When S_d is negative the drum 11 is moving 35 in the direction of motor 4, that is, in the hoisting direction.

It is also well understood that speeds of induction motors are often expressed in terms of slip or difference from synchronous speed; 40 and that the torque of such a motor varies substantially in direct proportion to its slip. Equation (III) then becomes

$$(IV) \quad S_c - S_a = S_d$$

45 where S_c = slip of motor 4 S_a = slip of motor 3.

When motor 3 is above synchronous speed, its slip is negative and Equation (IV) becomes

$$50 \quad (V) \quad S_c + S_a = S_d$$

Manifestly only upon change of torque or motor characteristic can S_d change.

Equation (V) represents the condition 55 when the drill is moving down freely or only slightly cutting the sides but not resting on the bottom of the hole. The equation thus represents the maximum rate of progress of the drill.

60 When the bit rests on the bottom, Equation (IV) takes on changed values. Let these be expressed by

$$(VI) \quad S_{cx} - S_{ax} = S_{dx}$$

65 where

S_{cx} = the slip of motor 4 caused by its lessened torque

S_{ax} = the slip of motor 3 caused by the load of the bit while cutting.

$S_{cx} = S_c$ minus the slip value represented by 70 the weight of the drill now resting on the bottom.

In Equation (V), S_d is caused by torque created by the descending drill stem. Therefore, when the bit is cutting on the bottom, it first utilizes the torque represented by S_a and then utilizes the torque represented by S_{ax} . The torque on the drill pipe then is proportional to $S_{ax} + S_d$.
75

When $S_{ax} = S_{cx}$, then from Equation (VI) 80 $S_{dx} = 0$. That is, the torsional load caused by the cutting of the bit will be limited to a value that may be readily predetermined and controlled.

For an infinitesimal period of time only 85 can the relation

$$S_{cx} - S_{ax} = S_{dx} = 0$$

hold true. This result follows for the reason 90 that since S_{cx} is less than S_c , the bit is pressing on bottom and is cutting. Therefore, a balanced or compensating relation must exist such that $S_{cx} - S_{ax} = S_{dx}$ equals some positive value, however small, and the bit is moving steadily downward. That is S_{ax} can never 95 equal S_{cx} except only by the application of load on motor 3 other than cutting. This condition might happen in boulders and the like, but evidently only slight increase in the torque of motor 4 will bring S_{dx} to definite 100 zero and even to negative value, i. e., upward movement of the drill will occur.

The operation of the drilling mechanism may also be analyzed by considering the torque conditions that prevail while the drill 105 is cutting. From the inherent characteristics of the differential mechanism, it is apparent that the total torque exerted by the motor 4 is transmitted by means of the gear-wheel 15 to the pinions of the intermediate device 19 and by them to the gear-wheel 13 in a reversed direction. It is also apparent that the total torque of the motor 4 is impressed upon the intermediate device 19 and the drum 11 in the direction of rotation of the motor 4, as 110 hereinbefore explained.

Under normal drilling conditions then, the total torque of the motor 4 will tend to raise 115 the drill 1 and the total power developed by the motor 4 will be transmitted through the differential mechanism to the gear-wheel 13 and will be utilized to turn the drill 1 in co-operation with the motor 3.

As the work of drilling progresses, it becomes necessary to increase the length of the 120 drill pipe and, consequently, its weight so that the torque which the drum 11 is called upon to exert becomes correspondingly greater. To provide this additional torque, it is necessary that the torque output and, 125 130

consequently, the power output of the motor 4 be increased. Since substantially all of the power output of the motor 4 is utilized for turning the drill 1, it is further necessary to 5 reduce the power output of the motor 3 a corresponding amount in order that the total power applied to the drill 1 will remain the same.

This readjustment of the ratio of the torque 10 supplied by the motors 3 and 4 must be made each time the weight of the drill pipe or the number of lines in the suspending tackle is changed in order that the pressure on the bit and the turning effort applied to it may be 15 kept substantially the same.

Thus the regulation is positive, accurate, sensitive, extremely rapid and such difficulties as twistoffs, breakage, excessive stresses, binding of drill, overloads and the like will 20 be prevented.

In Figure 4 a different type of drilling apparatus is illustrated, including a rotary drill 30 and a traveling screw device 31 that are controlled in accordance with the joint 25 action of the main driving motor 3 and the regulating motor 4, in a manner similar to that set forth in connection with Figure 3.

The driving motor 3 again drives the rotary table 8 through a suitable bevel gear 23 30 and also drives a belt 36, or other mechanical connection that is attached to a rotary nut 34, which co-operates with a traveling screw member 33. The regulating motor 4 is provided with an operating shaft 32 having a 35 square shank that slidably engages a longitudinal recess in one end of traveling screw 33. The opposite end of the traveling screw is secured to the upper end of the drill 30 by means of a suitable cable 35.

40 The operation of the apparatus shown in Figure 4 may be set forth as follows:

Under no load conditions, that is, with no cutting action of the tool, the drive arrangement is such that the traveling screw 33 runs 45 faster than the rotary nut 34 and thus the drill 30 is advanced at a definite rate, as will be understood. If the speed of the main driving motor 3 remains substantially constant, while the regulating motor 4 is provided with a variable secondary resistor, then the advance of the drill 30 and the pressure exerted thereby will respond to the 50 slowing down of the regulating motor 4 as it takes a load that is determined by the hardness of the material being drilled.

The apparatus illustrated in Figure 4 may also be utilized for horizontal earth drilling, such as tunnel boring, by substituting a horizontal drill for the swivel illustrated at the 55 left hand end of the traveling screw 33. In this case, motor 3 will drive the rotary nut 34 only, while motor 4 will drive the traveling screw 33 as already described.

In Figure 5, I illustrate the application of 60 my method of control to an electric planer,

or the like. In this apparatus the main motor 3 drives one outer member or gear-wheel 13 of the differential device 5, while the regulating motor 4 drives the other outer member or gear-wheel 15, as described in connection with Figure 3. The intermediate or differential member 18 is provided with a shaft 40 that drives a pinion or gear wheel 42 to mesh with a rack member 43. This rack member is mounted upon the movable table or platen 70 of a planer, or the like. Movement of the platen is effected in either direction by reason of a predetermined difference in the operating speeds of the two motors. The differential member 18, which drives the platen, thus 75 rotates in the one or the other direction to produce the cutting and the return strokes.

To provide the necessary reversal in the direction of operation of the platen, a pair 80 of dogs or levers 44 and 45 are adapted to engage switches 46 and 47, jointly, at the ends of the cutting and return strokes. In this way the speeds of the motors 3 and 4 may be suitably changed by the movement of the platen 85 itself to provide the desired slow cutting 90 stroke and rapid return stroke, as more fully hereinafter described.

Whenever torque is transmitted by the intermediate member 18 through shaft 40 and pinion 42 to move the platen 41, the load will 95 be carried by the main driving motor 3 if regulating motor 4 and the corresponding outer gear-wheel 15 be stationary. If the motor 4 and the gear-wheel 15 are running, the main driving motor 3 must also drive the 100 regulating motor 4 if the speed of the differential member 18 is to be maintained at the proper value. In this case therefore, the regulating motor 4 becomes a generator to return 105 energy to the supply circuit.

The regenerative load on the regulating motor 4 equals the actual power required to move the platen, minus the electrical losses of the regulating motor 4 and all the mechanical losses of that motor and of the driving 110 mechanism. The motor load on the main driving motor 3 equals the regenerative load of the regulating motor 4 plus the power required to move the platen 41 together with all of the electrical and mechanical losses of the 115 two motors 3 and 4, and the entire driving mechanism.

When the platen 41 reaches the end of a stroke, the switches 46 and 47 are operated by the corresponding dog 44 or 45 to change the 120 speed relations of the two motors so that regulating motor 4 will now run faster than main driving motor 3. This action reverses the direction of rotation of the differential member 18 and, therefore, the direction of operation of the platen 41. The desired speed changes upon reversal of the platen may be effected by changing the number of motor 125 poles or varying the secondary-circuit resistance, for example. However, such opera- 130

tion is well known in the art and forms no part of my present invention. I have not deemed it necessary, therefore, to further illustrate or describe such a system.

5 In this way the actual direction of rotation of the two motors is never changed, but only the relative values of the speeds, in order to reverse the travel of the planer parts. A very flexible planer control employing only
 10 two machines is thus provided, together with a regenerative braking effect in reversing the travel of the platen. Moreover the resistance encountered by the cutting tool will determine the speed of operation of the platen,
 15 which will automatically increase in speed whenever no material is actually being cut and will automatically slow down as soon as the material is again encountered.

It will be seen that I have thus provided a
 20 very flexible and effective method of control that is particularly adapted to any type of earth drilling, or the like, where cutting tools are used on or in different materials. This method of control automatically varies the
 25 rate of advance of the cutting tool in accordance with the material being cut and maintains the maximum rate of progress that is consistent with safety. By employing this invention the driller will not be required
 30 through the sense of touch, sight and hearing to personally endeavor to regulate the pressure and progress of the drill bit. Instead he will merely close the necessary electric switches, whereupon the apparatus will function automatically throughout the full length
 35 of the drill stem, and the driller during that time will be free to give attention to other matters.

In other words, most of the so-called "accidents" and supposedly "unavoidable troubles" in drilling, as practiced prior to the present invention, are traceable to inherently imperfect methods of hand regulation or the like, whereas the present invention will automatically prevent the occurrences of such accidents and troubles by regulating the drilling operation in accordance with the material being drilled.

40 I do not wish to be restricted to the specific structural details, circuit connections or arrangement of parts herein set forth, as various modifications thereof may be made without departing from the spirit and scope of
 45 my invention. I desire, therefore, that only such limitations shall be imposed as are indicated in the appended claims.

I claim as my invention:

1. The combination with a working member, of means including two non-interacting alternating current motors for respectively effecting rotational and translational movements of said member, and means responsive to the load on one motor for controlling the
 50 effect of the other to thereby automatically
 55 regulate the rate, and the direction, of the translational movement of said member.

2. The combination with a working member, of means which includes two non-interacting alternating current motors for respectively effecting rotational and translational movements of said member, and means responsive to the resistance encountered by said member, for controlling the rate, and the direction, of its translational movement.

In testimony whereof, I have hereunto subscribed my name this twentieth day of January, 1923.

FREDERIC W. HILD.
